US00D695611S

(12) **United States Design Patent**
Burleson, Jr. et al.

(10) **Patent No.:** **US D695,611 S**
(45) **Date of Patent:** **** Dec. 17, 2013**

(54) **CAN END**

(71) Applicant: **Silgan Containers LLC**, Woodland Hills, CA (US)

(72) Inventors: **Lynn A. Burleson, Jr.**, Fort Dodge, IA (US); **John L. Phillips**, Monona, WI (US); **Donald M. Gust**, Oconomowoc, WI (US); **Rohm E. Bloedorn**, Delafield, WI (US)

(73) Assignee: **Silgan Containers LLC**, Woodland Hills, CA (US)

(**) Term: **14 Years**

(21) Appl. No.: **29/455,852**

(22) Filed: **May 24, 2013**

Related U.S. Application Data

(63) Continuation of application No. 29/398,281, filed on Jul. 28, 2011, now Pat. No. Des. 685,266, which is a continuation-in-part of application No. 29/377,154, filed on Oct. 18, 2010, now Pat. No. Des. 653,109.

U.S. Appl. No. 29/398,281, filed Jul. 28, 2011, Burleson Jr. et al.

Primary Examiner — Susan Bennett Hattan

(74) *Attorney, Agent, or Firm* — Reinhart Boerner Van Deuren s.c.

(57) **CLAIM**

We claim the ornamental design for a can end, as shown and described.

DESCRIPTION

FIG. 1 is a perspective view of an embodiment of the claimed design;

FIG. 2 is a front view of the claimed design of FIG. 1, the rear view, the left side view and the right side view being the same as the front view;

FIG. 3 is a top view of the claimed design of FIG. 1;

FIG. 4 is a bottom view of the claimed design of FIG. 1;

FIG. 5 is a sectional view taken along section line 5-5 in FIG. 3;

FIG. 6 is a perspective view of another embodiment of the claimed design;

FIG. 7 is a front view of the claimed design of FIG. 6, the rear view, the left side view and the right side view being the same as the front view;

FIG. 8 is a top view of the claimed design of FIG. 6;

FIG. 9 is a bottom view of the claimed design of FIG. 6; and,

FIG. 10 is a sectional view taken along section line 10-10 in FIG. 8.

The ornamental design which is claimed is shown in solid lines in the drawings. The broken lines in the drawings are for illustrative purposes only and form no part of the claimed design.

1 Claim, 6 Drawing Sheets
